UNITED STATES PATENT OFFICE.

CHARLES A. WAKEMAN, OF OSHKOSH, WISCONSIN.

WOOD-SHAVING MACHINE.

1,305,421.

Specification of Letters Patent. Patented June 3, 1919.

Application filed December 31, 1918. Serial No. 269,153.

To all whom it may concern:

Be it known that I, CHARLES A. WAKEMAN, a citizen of the United States, and resident of Oshkosh, in the county of Winnebago and State of Wisconsin, have invented certain new and useful Improvements in Wood-Shaving Machines; and I do hereby declare that the following is a full, clear, and exact description thereof.

10 My invention relates to new and useful improvements in machines for cutting thin knife-edged shavings or the like, of that type wherein there is provided a rotary knife head and means for feeding work against one side of the knife head and simultaneously rotating the work.

15 It is in general the object of my invention to simplify and otherwise improve the structure and to increase the efficiency of machines of this character.

It is more particularly my object to insure an even feeding movement of the work to the knives of the cutting head, and to maintain a fairly constant relative speed of rotation of the knife blades with respect to the speed of travel of the peripheral surface of the log, in view of the reduction of the log by cutting, and the consequent diminution of the diameter of the log. It is more particularly my object in this connection to provide an arrangement for automatically varying the gear ratio between the cutter drive shaft and a shaft for feeding the work, to compensate for the reduction in diameter of the work.

A further object resides in the provision of an arrangement for automatically halting feeding movement of the work toward the cutter head, and for readily instituting said feeding movement at any desired position of the work carrying means with respect to the cutter head.

A still further object resides in the provision of a machine of this character where in a pair of logs may be held against opposite portions of the cutter head to utilize said cutter head to a maximum extent.

With the above and other objects and advantages in view, which will be apparent as the description proceeds, my invention resides in the novel features of construction, combination and arrangement of parts as hereinafter more particularly described and defined by the appended claims.

In the accompanying drawings: 55

Figure 1 is a side elevational view of a wood shaving machine embodying my invention, portions of the log feeding mechanism being broken away.

Fig. 2 is a plan view of the machine. 60

Fig. 3 is a sectional view through the machine on a plane indicated by the broken line 3—3 of Fig. 2.

Referring now more particularly to the accompanying drawings, there is provided a main frame including an upper pair of side sills 10 and a lower pair of side sills 11 connected with the upper sills by vertical and horizontal end bars 12, the main frame being supported on legs 13. A main shaft 14 extends longitudinally through the frame, one end of the shaft carrying belt pulleys 15 while the other end of the shaft carries a circular cutting head 16 of type common in machines of this character, and provided 70 with radial knife blades 17 projecting from its outer face.

For utilizing the cutting action of these blades both above and below the rotative axis of the cutter head, upper and lower log 80 carriages 18 and 19 are provided, the upper carriage seating on the main frame and held thereto by channel plates 20 engaging under out-turned track portions of the upper sills 11, while the lower carriage 19 is held 85 against the bottom of the main frame by similar channel plates 21 engaged on out-turned track projections of the lower pair of main frame sills 11.

Inasmuch as the work carriages and the 90 operating means of the carriages are identical, but one will be described specifically, the corresponding numerals applying to both carriages. Each carriage is provided at its forward end with outwardly and then 95 forwardly extending arms 22 and 23 respectively embracing the cutter head 16. A screw 24 is transversely threaded in the arm 22, carrying a point 25 engageable with one end of the log or block to be cut, while a mandrel 26 is mounted in the outer end of the other arm 23 for engagement with the log or block, this mandrel being driven by a bevel gear connection 27 with a shaft 28 which is driven by a bevel gear connection 29 with a 100 shaft 30 driven in turn by a bevel gear connection 31 with a shaft 32 journaled longitudinally on the carriage. The shafts 28 and

30 are carried by the angularly disposed portions of the arm 23, to thus provide clearance for movement of the carriages with respect to the cutter head to feed work theretoward. The shaft 32 is driven by a crown pulley 33 which is splined thereon and which is driven by a belt 34 trained about a pulley on the main shaft 14. The hub of the pulley 33 is grooved to receive the bearing 5 portion of a bracket 35 projecting from the main frame to hold the pulley against movement out of alignment with the pulley of the main shaft, said bracket 35 and the pulley belt projecting through the cutaway 10 intermediate portion of the carriage whereby movement of the carriage is permitted without interference with continuous driving operation of the various shafts carried thereby.

For feeding the carriages rearwardly of the body frame, to thus feed work carried by their arms toward the cutter head in a manner whereby the speed of feeding movement is automatically progressively increased to compensate for the progressive decrease of 20 peripheral surface of the work, a counter shaft 36 is mounted in bearings 37 projecting laterally from the main frame, and a parallel screw shaft 38 is also mounted on the side of the main frame and is engageable 25 by nut sections 39 carried by the carriages. The shaft 36 and screw shaft 38 are connected by a reducing train of gears 40, of that type including series of double gears loose on the shaft and meshing with end 30 gears fixed on the shafts, although any other preferably conventional reducing drive may be employed. A conical belt pulley 41 is fixed on the main drive shaft 14, having its smaller end disposed forwardly and a conical pulley 42 is disposed on the shaft 36 having its smaller end disposed rearwardly of the machine. A belt 43 is trained about these pulleys and is engaged by shifter arms 44 depending from the upper carriage. Thus 40 the speed imparted to the carriage feeding mechanism is automatically increased upon rearward movement of the carriages, and this increase of speed is proportional to the decrease of peripheral area of the work as it 45 is cut, thus insuring an even cutting action on the work throughout the entire operation, and at the same time affording a positive feed for the work against the cutting blades.

The nut sections 39 carried by the carriages are in the form of arcuate head portions provided with thread sections engageable with threads of the screw shaft 38 and these head portions are carried on shanks 45 which are slidable in transverse dove-tail 50 channelways in blocks 46 at the sides of the carriages whereby the nut sections may be shifted from the screw shaft to stop the feeding action and to permit a rapid outward shifting movement of the carriages to initial 55 position. In the present construction, these

nut sections are operated simultaneously by an angle lever 47 having one arm pivoted to the channel block 46 of the upper carriage and having its other arm extended upwardly to form a handle, the angle portion of this 70 lever being pivoted to the shank 45 of the upper nut section and pivoted to a link 48 which is in turn pivoted to a lever 49 pivotally connected with the lower channel block 46 and the shank 45 of the lower nut 75 section. Thus rocking movement of the lever 47 will procure engagement or disengagement of the nut sections, the lever being normally locked in position holding the nut sections in engagement with the screw shaft 80 by a pawl 50 pivoted on the upper carriage and resiliently urged to engage the lever by a spring 51. The lever is resiliently urged against the locking action of this pawl by a spring 52, and to control movement of the 85 lever from the front end of the machine, a rod 53 extends forwardly from the upper end of the lever, being guided in an upstanding eye 54 on the carriage, and terminates in a suitable handle grip forwardly of the cutter head 16.

For automatically releasing the nut sections at a desired inward limit of feeding movement of the carriages, a cam projection 55 is carried on an arm upstanding 95 on and laterally offset from the rear of the main frame and this cam portion is engageable with an abutment pin 56 on the lever pawl 50 to rock said pawl against the action of its spring 51.

I have thus provided a simple and efficient machine for cutting thin knife-edged shavings or the like, which is automatic in operation with the exception of resetting the feeding carriages and securing fresh work material thereto.

While I have shown a preferred embodiment of my invention, it will be appreciated that various changes and modifications of structure may be resorted to without departing in any manner from the spirit of the invention, and that so far as certain phases of the invention are concerned, but a single carriage may be employed for holding work material.

What is claimed is:

1. A machine of the class described including a main frame, a rotating knife head carried by the main frame, a pair of carriages slidably carried by the main frame, means carried by said carriages for holding work for engagement by opposite portions of the knife head, a driven screw shaft, and nut sections carried by the carriages and engageable with the screw shaft.

2. A machine of the class described including a main frame, a rotating knife head carried by the main frame, a pair of carriages slidably carried by the main frame, means carried by said carriages for

holding work for engagement by opposite portions of the knife head, a driven screw shaft, nut sections carried by the carriages and engageable with the screw shaft, and 5 lever means connecting the nut members for procuring simultaneous movement thereof.

3. A machine of the class described including a main frame, a drive shaft carried by the main frame, a knife head on said 10 drive shaft, a carriage slideable on the main frame, outwardly and forwardly extending arms on the carriage embracing the knife head, means at the free end of said arms for holding work, means carried by the carriage 15 for rotating the work held by said arms, and means for moving the carriage to feed work toward the cutter head.

4. A machine of the class described including a main frame, a drive shaft carried 20 by the main frame, a knife head on said drive shaft, a carriage slideable on the main frame, means carried by the carriage for holding work to be engaged by the cutter head, a shaft on the carriage, means oper- 25 able by said carriage shaft for rotating the work, a pulley splined on the shaft, a bear-

ing bracket for said pulley carried by the main frame, and a drive connection between said pulley and the first named shaft.

5. A machine of the class described including a main frame, a drive shaft carried by the main frame, a knife head on said drive shaft, a carriage slideable on the main frame, outwardly and forwardly extending arms on the carriage embracing the knife head, means at the free ends of said arms for holding work including a mandrel, and means for driving said mandrel to rotate the work comprising a shaft mounted on the carriage and extending longitudinally of its 30 direction of sliding movement, a splined drive connection for said shaft, and a pair of gear connected shafts carried by one of the carriage arms and having gear connection respectively with the said longitudinal 35 shaft and the mandrel.

In testimony that I claim the foregoing I have hereunto set my hand at Milwaukee, in the county of Milwaukee and State of Wisconsin.

CHARLES A. WAKEMAN.
